CLAIM

The ornamental design for a bottle, as shown and described.

DESCRIPTION

FIG. 1 is a top, rear, left perspective view of a bottle showing the present design;

FIG. 2 is a left side elevational view of the bottle of FIG. 1; FIG. 3 is a right side elevational view of the bottle of FIG. 1;

FIG. 4 is a front elevational view of the bottle of FIG. 1; FIG. 5 is a rear elevational view of the bottle of FIG. 1; and, FIG. 6 is a top plan view of the bottle of FIG. 1.

The evenly broken lines are shown for the purpose of illustrating portions of the bottle that form no part of the design. The dash-dot-dash broken lines define the boundary of the design and form no part thereof. The appearance within the leaf-shaped outlines on the bottle form no part of the claimed design.
